UNITED STATES PATENT OFFICE.

ALBERT MONKIAWICZ, OF NEW BRITAIN, CONNECTICUT.

GRINDING-WHEEL.

1,092,588.

Specification of Letters Patent.

Patented Apr. 7, 1914.

Application filed January 5, 1914. Serial No. 810,525.

To all whom it may concern:

Be it known that I, ALBERT MONKIAWICZ, a citizen of Russia, residing at New Britain, in the county of Hartford and State of Connecticut, have invented certain new and useful Improvements in Grinding-Wheels, of which the following is a specification.

My invention relates to improvements in grinding wheels, and the object of my improvement is to produce a wheel that is built up of units of fabric and abrasive material and which has certain qualities which make it adapted in a superior manner for certain kinds of work.

15 In the accompanying drawing:—Figure 1 is a side elevation of my improved grinding wheel. Fig. 2 is an end elevation of the same. Fig. 3 is a side elevation on a reduced scale of one of my grinding wheels in a pressure frame. Fig. 4 is a side elevation on the same scale as Fig. 1 of one of the units used in building up my grinding wheel. Fig. 5 is an end elevation in outline of the same. Fig. 6 is a fragmentary view, part in 20 side elevation and part in section, on an enlarged scale, on the line $\alpha\alpha$ of Fig. 1.

25 My grinding wheel is built up of a plurality of units 10 as shown in Figs. 4 and 5 in a special manner to be described by means of glue and emery. The units 10 are themselves built up of a plurality of layers of fabric 11, as shown in Fig. 6, held together by concentric rows of stitching 12 and have a central hole 13 for the shaft and are precisely the same as are used in making up 30 what is known as a cloth buffing wheel.

35 In the building up process for the grinding wheel it is convenient to use some form of pressure frame 14, such as shown in Fig. 3. In the first step, a unit 10 is placed in the frame 14. Then a layer of glue is applied to the exposed upper surface. Then a layer of emery is sprinkled over the surface of the glue. Then a layer of glue is applied 40 to the lower surface of the second unit 10, after which the said second unit 10 is laid on the first unit 10. In a similar manner others of the units 10 are superimposed upon those already in the frame until the desired thick-

ness for the finished grinding wheel is obtained. Finally pressure is applied by means of the clamping nut 15. After being under pressure for an hour or so the wheel is removed from the frame and set away for a period to permit of drying thoroughly.

55

The description given above applies to building up the body of the wheel. The finishing of the periphery 16 follows, and is effected in the following manner: The wheel body is mounted on a shaft and rotated and a tool of suitable character is applied to the surface to true the same, after which a layer of glue is applied and on this a layer of emery. Then a second layer of glue and emery may be applied. The result is that the 60 periphery 16 of the finished grinding wheel consists of a layer of abrasive material.

65 The character 17 designates the layer between the adjacent units 10, and which also has abrasive material. And I prefer to use 70 the same grade of abrasive material in the said layer 17 as in the periphery 16. This may consist of what is known as 120 grade of emery or 150 grade or some other grade suitable for the work to be done on the grinding 75 wheel.

80 My grinding wheel as described is especially designed for high grade work. For use for such work the use of the emery in the layer 17 between the units 10 is of especial 85 importance. The omission of the emery here, and the use of glue alone, effects an inferior result.

85 The periphery as shown is finished off cylindrical. In special cases this may be changed and the shape may be made to conform to the shape of the work. The end walls of the complete wheel may also be finished, and for doing this I prefer to use a layer of glue on which a layer of emery has 90 been sprinkled, as in the case of the layers between adjacent units 10, and I prefer to use the same grade of emery here as is used in the other parts of the wheel as described.

95 I claim as my invention:—

A grinding wheel built up of a plurality of layers of fabric and provided on the periphery with a layer of abrasive material,

the said fabric being subdivided into a plurality of units, each of the said units being composed of a plurality of layers of fabric and which are secured together by concentric 5 rows of stitching, the said units being secured one to the other successively by means of glue, and an appreciable quantity of

abrasive material being commingled with the said glue and thereby interposed between the opposed faces of the said units.

ALBERT MONKIAWICZ.
